UNITED STATES PATENT OFFICE.

THOMAS F. DUFF, OF SPOKANE, WASHINGTON, ASSIGNOR OF ONE-THIRD TO MAX TONN, OF SPOKANE, WASHINGTON.

LINE-CASTING MACHINE.

Application filed July 22, 1922. Serial No. 576,803.

To all whom it may concern:

Be it known that I, THOMAS F. DUFF, a citizen of the United States, residing at Spokane, in Spokane County and State of 5 Washington, have invented certain new and useful Improvements in Line-Casting Machines, of which the following is a specification.

The present invention relates to improvements in line casting machines of the linotype class, and is designed especially as a control and safety device to prevent operation of such machines by rendering inoperative the friction clutch mechanism which 10 controls the machine when the mold carrying slide is disconnected, as when parts are removed or pulled out of line for repairs.

In working about the linotype machine, the clothes of the operator sometimes catch 20 on the clutch lever, or through other accident, the clutch lever is operated to throw the machine into operation. Should such an accident occur while the power is applied to the machine, as the clutch lever is shifted, 25 when all parts of the machine are not in correct and relative positions, disastrous results follow.

The control and safety device of the present invention is adapted especially to 30 that class of line casting machines which employ a line-delivery slide which is retracted through its rear connection, line-delivery cam roller, arm, utilized for the forward or backward thrust of the line-delivery slide, which is accomplished by the 35 use of this line-delivery cam roller arm and which is journaled to its shaft, prior to and subsequent to each casting operation. And the invention also embodies means for co- 40 action with the vertical lever and the stop seat thereon for the purpose of terminating one complete revolution of the operating cams employed in these machines.

Heretofore, in the operation of machines 45 of this character, the mold carrying slide is frequently disconnected from its source of power, and pulled forward out of operative position, for many purposes in connection with its care and usage. Practical experience has demonstrated that safety means 50 should be provided on the machine, to prevent accidental or inadvertent shifting of the lever of the clutch control and consequent starting of the machine while such conditions exist.

The primary object of the invention is to provide a simple control device by means of which the first lug of the vertical lever forming part of the machine, is rendered inoperative unless in correct position with 60 relation to the machine. Thus the control device is designed to engage the roll of the mold slide wheel whenever the lever or handle of the mold slide is depressed for purposes above mentioned. This depression 65 of the lever raises the mold slide wheel out of engagement with the mold slide notch and this action brings the safety device of the invention into effective use, in engagement with the wheel. The invention consists 70 in certain novel combinations and arrangements of parts as will be hereinafter more specifically pointed out and claimed.

In the accompanying drawings I have illustrated one complete example of the 75 physical embodiment of my invention, wherein the parts are combined and arranged according to the best mode I have thus far devised for the practical application of the principles of my invention. 80

The drawings disclose such elements or members of the machine as are necessary to ascertain and understand the relation of parts and the application to the machine of the safety locking device of my invention. 85

Figure 1 is a perspective view showing the locking or safety device of my invention with the vertical starting lever, the device being attached to the upper lug of this lever, which lug is slotted to receive and support 90 the locking device.

Figure 2 is a view showing the relation of the locking device of my invention to the line-delivery operating cam, and the mold slide lever wheel as seen from above. 95

Figure 3 is a view showing parts of Figure 2 in elevation, together with the pump cylinder and connections.

Figure 4 is an enlarged, detail perspective view of the safety locking device detached. 100

The safety locking device of the invention is an attachment which is readily applicable for use with the line casting machine, and as seen in Figure 4 includes a metal plate 1 fashioned with a reduced, longitudinal extension 2 at one end for attachment to the machine as will be described. At its opposite end, the plate is bent to form an angular pawl 3, disposed in a plane at right angles to the body of the plate 1, which is designed 105 110

to co-act with the mold slide operating mechanism.

A second pawl 4 is carried by the plate 1, the pawl being fashioned with an attaching bracket 4' and secured to the plate 1 by means of the slot 5 in the said plate, a clamp plate 6, and clamp screws 7. The clamp plate is located at the back of the plate 1, and the screws 7 which pass through the angle bracket 4' and slotted plate 1, are anchored in this clamp plate, in order that the pawl 4 may be adjusted longitudinally of the supporting plate 1 and secured in adjusted position.

15 The two pawls 3, and 4 are located in vertical planes, spaced apart, and have their upper and lower edges curled or turned over at 8 and 9 respectively in order that the machine may be permitted to turn backward without breaking off these pawls 3 and 4.

The plate 1 of the device is attached to the lug 10 which is slotted or formed with an aperture 11 to receive the extension 2 of the plate. The attachment is thus supported on or carried by the vertical starting lever 12, of which the lug 10 forms a part, and the attachment, through its extension may be adjusted relatively to the lug and lever and secured in adjusted position by turning tight the set screws 13 and 14, respectively, of the lug which engages the extension in the aperture or socket 11. The vertical starting lever 12 is supported on its shaft 15 and the stop lever 16, when depressed engages the lower end of the lever 17 therebelow, to cause the release of the clutch.

The numeral 18 designates one of the cams of the machine, journaled on the cam shaft 19, which cam carries the automatic safety or stopping pawl 20 pivoted to the cam at 21. One of the functions of the cam is to operate the line-delivery slide lever 22 which has a bearing 23 on the machine frame 23', and a roller arm 24 on which the line-delivery slide roller 25 is journaled. The line-delivery cam roller 25 rotates on the outer surface of the cam 18, the roller 25 being shown out of engagement with the cam, in Figure 2, and the stopping pawl 20 carried by the cam 18 is moved by the cam roller 25.

The lug 10 operates the mold slide lever 26 by co-action with the mold slide lever 55 wheel 27 in Figure 2, and causes the return to place of the line-delivery lever 24 and mold slide lever 26 after their respective movements.

In Figures 2 and 3 the stopping pawl 20, which when in normal position, or unlocked and released, permits the machine to operate through one revolution, but in Figure 2, the pawl 3 of the locking device which is engaged with the mold slide lever wheel 27 (shown in lowered position) prevents the

stopping pawl 20 from being moved by pulling the starting lever 12 in usual manner. The stopping pawl 20 engages the seat of the stop lever 16 to stop the operation of the device, and said pawl is pushed from its seat by cam roller 25 to start the operation.

Under usual conditions of operation, the line-slide delivery arm 24 is moved to shift the clutch and start the machine, the wheel or roller 25 thereon engages the stopping pawl 20 and pushes said pawl from the stop lever seat 16 upon which it rested. But with the pawl 4 engaging the pawl 20, the stopping pawl can not be moved until the mold slide lever 26 has been raised by the operator, permitting the pawl 3 to pass to the right in Figure 2, which permits the stopping pawl 20 to move to the right and the machine is then free to operate.

Having thus fully described my invention, what I claim and desire to secure by Letters Patent is:

1. In a linotype machine, the combination with the vertical starting lever and mold slide lever and the wheel on the latter, of an arm carried by the vertical starting lever, and a wheel on said arm adapted to engage said pawl while the latter is depressed to hold the vertical starting lever against operation.

2. In a linotype machine the combination with the vertical starting lever and its upper lug having a socket therein, of an arm adapted to fit said socket and means for holding said arm in adjusted position, the mold slide lever and its wheel, and a pawl on said arm adapted to engage said wheel while the latter is depressed to hold the vertical starting lever against operation.

3. The combination with a starting lever, a cam for operating the line slide delivery lever and a stopping pawl on said cam, the mold slide lever and its wheel, and means carried by said vertical starting lever for engagement with said stopping pawl and wheel, to hold the vertical starting lever against operation for the purpose described.

4. In combination with the vertical starting lever, a cam for operating the line slide delivery lever and a stopping pawl on said cam, and the mold slide lever and its wheel, of an adjustable arm and means for securing said arm against said vertical starting lever, a pawl on said arm for engagement with said wheel, and a second pawl on said arm for engagement with said stopping pawl, whereby the vertical starting lever is held against operation for the purpose described.

5. In combination with the vertical starting lever, a cam for operating the line slide delivery lever and a stopping pawl on said cam, and the mold slide lever and its wheel, of a perforated lug on said vertical starting lever, an arm having an extension and means for holding said extension in adjusted position.

tion in said lug, an angular pawl on said arm adapted to engage said wheel, and an adjustable, angular pawl on said arm adapted to engage said stopping pawl, for the 5 purpose described.

6. In a linotype machine the combination with the vertical starting lever, of a safety device comprising an arm and means for securing said arm in adjusted position on 10 said lever, an angular pawl at the free end

of said arm, and an intermediate, adjustable pawl on said arm.

7. An attachment comprising a slotted plate having an end, angular pawl, a back plate, a bracket plate and screws for securing said back plate and bracket plate in adjusted position on the slotted plate, and an angular pawl on said bracket plate. 15

In testimony whereof I affix my signature.

THOMAS F. DUFF.
